UNITED STATES PATENT OFFICE.

ALVA DANIEL KOSS, OF CERRO GORDO, ILLINOIS.

COIN-CONTAINER FOR MAIL-BOXES.

1,315,133.

Specification of Letters Patent.

Patented Sept. 2, 1919.

Application filed April 2, 1919. Serial No. 287,008.

To all whom it may concern:

Be it known that I, ALVA DANIEL Koss, a citizen of the United States, residing at Cerro Gordo, in the county of Piatt and State of Illinois, have invented certain new and useful Improvements in Coin-Containers for Mail-Boxes; and I do hereby declare the following to be a full, clear, and exact description of the invention, such as will enable others skilled in the art to which it appertains to make and use the same.

My invention relates to improvements in rural delivery mail boxes and more particularly to coin receptacles therefor.

15 An important object of this invention is to provide a mail box having a coin receiving receptacle with novel receiving and dispensing coin means whereby the coin may be expeditiously handled with the possibility 20 of loss reduced to a minimum.

A further object of the invention is to provide a device of the character described, which is simple, neat in appearance, and cheap to manufacture.

25 Other objects and advantages of the invention will be apparent during the course of the following description.

In the accompanying drawings forming a part of this specification, and in which like numerals are employed to designate like parts throughout the same,

Figure 1 is a longitudinal section through a mail box having my improved coin handling device applied thereto,

35 Fig. 2 is an end elevation of the same, and

Fig. 3 is a longitudinal section through the same taken on line 3—3 of Fig. 2.

In the drawings wherein for the purpose of illustration is shown the preferred embodiment of my invention, the numeral 5 generally designates a rural mail box which is rectangular in form and is provided with a horizontally hinged end closure 6. The upper portion of the closure 6 is provided 40 with a flange 7 overlapping the top 8 of the box. An operating arm 9 is connected to the flange 7 and may be engaged by a spring arm 10 carried by the top 8 of the receptacle to retain the closure 6 in an upright position.

45 As clearly shown in Figs. 1 and 3, the box 5 is provided in its upper side with an inclined chute 11 having a closure 12 horizontally hinged thereto as indicated at 13. The closure plate 12 extends below the under

side of the chute 11 to effectively prevent 55 rain and so forth entering the chute. The chute 11 has communication with a rectangular coin receptacle 14. The receptacle 14 is provided with end walls 15 and 16. A bottom wall 17 is horizontally hinged to the 60 end wall 15 as shown at 18 and is provided with an operating flange or finger 19. As indicated in Fig. 1 the flange or operating member 19 terminates flush with the front of the receptacle 14 and is disposed horizontally whereby when the flange is drawn downwardly by the fingers the coins will fall into the palm of the hand. A coil spring 20 is connected to the forward portion of the bottom 17 and the top 8 and is 65 adapted to normally retain the receptacle closed. As clearly illustrated in Fig. 3, the receptacle 14 is secured to the top 8 by suitable retaining elements 21 which extend through lateral projecting flanges 22 of the 70 side walls of the receptacle.

In the use of my invention, it will be apparent that the coins are passed into the receptacle 14 through the chute 11 either for the purpose of prepaying the postage 80 within the box or for purchasing new stamps. A flag 22' is pivoted as at 23 to the chute 11 for calling the attention of the postman to the box.

While I have shown and described the 85 preferred embodiment of my invention, it is understood that I may make such minor changes in arrangement and construction of parts, as will remain within the spirit of the invention and scope of the appended 90 claim.

Having thus described my invention, what I claim is:—

A coin receptacle for mail boxes comprising a rectangular casing disposed within the 95 mail box and having a horizontally hinged bottom, spring means normally retaining said bottom in engagement with the casing, and a horizontally disposed operating member carried by the forward end portion of 100 the bottom and terminating flush with the same.

In testimony whereof I affix my signature in presence of two witnesses.

ALVA DANIEL KOSS.

Witnesses:

CHAS. TAYLOR,
J. R. McCORD.
